UNITED STATES PATENT OFFICE.

SAMUEL E. ANDRESS, OF WILMINGTON, DELAWARE.

APPARATUS FOR COATING SHEET METAL.

No. 908,829.

Specification of Letters Patent.

Patented Jan. 5, 1909.

Application filed August 19, 1908. Serial No. 449,272.

To all whom it may concern:

Be it known that I, SAMUEL E. ANDRESS, a citizen of the United States, residing at Wilmington, in the county of New Castle and State of Delaware, have invented certain new and useful Improvements in Apparatus for Coating Sheet Metal; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in apparatus for galvanizing iron, etc., and comprises essentially certain adjustable mechanism whereby the rollers between which the sheets of metal are drawn, may be regulated, and also in the provision of a swinging guide frame so arranged as to allow for variation in the thicknesses of the plates being coated and also to give ready access to a plate which it might be desired to withdraw from the bath for any purpose.

The invention comprises various details of construction and combinations and arrangements of parts which will be hereinafter fully described and then specifically defined in the appended claims.

I illustrate my invention in the accompanying drawings, in which:—

Figure 1 is a side elevation of the apparatus embodying my invention. Fig. 2 is a top plan view. Fig. 3 is an enlarged detail in side elevation, and Fig. 4 is a detail view of a hanger plate.

Reference now being had to the details of the drawings by letter, A, A designate two beams adapted to have pivotal connection at A' with any fixed object, either the wall of a vat or pot that is adapted to contain the molten metal or adjacent thereto, and so arranged as to allow the frame of which said beams are a part to have swinging movements upon said pivots. Upon each of said beams is mounted a drop frame, designated by letter B, and upon the horizontally disposed portions of said frames B are mounted the bearing boxes p and p', said boxes having flanges at their lower edges and adapted to straddle the frames, as shown clearly in the drawings. Mounted respectively in said

bearings are the two rollers P and P'. A gear wheel O is fastened to the spindle end of the roller P'.

N designates a shaft mounted in suitable bearings in the beams A and a driving pulley N' is fixed to one end of the shaft N and to which power may be applied. A hollow gear wheel, designated by letter M, is fixed to the shaft N and is made up of two circular disks connected together by a series of pins m spaced apart, while the sides of said wheel M are provided with openings m'. Said pins m are spaced apart suitable distances in order to receive the teeth of the gear wheel O. Said form of construction of hollow gear wheel as set forth is for the purpose of allowing any molten metal which might adhere to the teeth of the gear wheel O to be discharged from between the teeth thereof as it intermeshes with the teeth m, thereby clearing the gear wheel O of such accumulation of metal which, in the case of two solid gear wheels intermeshing, becomes objectionable and will cause an imperfect product in the coating of sheets of metal. This idea, however, of a solid pinion or gear wheel intermeshing with a hollow one for the purpose described, forms no part of the present invention but is made the subject-matter of a separate co-pending application Serial No. 449,272, filed in the U. S. Patent Office upon August 19, 1908.

A cradle made up of longitudinally disposed curved bars H is fixed to said beams A and B in the manner shown clearly in Figs. 1 and 2 of the drawings. Said bars H are formed of bars curved edgewise and are held together by means of cross-rods or bars i, suitable spacing washers or tubes l being interposed between said bars, as shown clearly in Fig. 2 of the drawings. The inner curved ends of the bars H are fastened to the frame B by means of a cross-bar or rod i at a location underneath the bearing blocks p, as shown clearly in Fig. 1 of the drawings. A second cradle is made up of the curved bars H' similar in construction to the bars H described, said bars being held together by means of cross rods i' and the inner curved ends of the bars H' are pivotally mounted upon a rod H² which is mounted adjacent to the rod which fastens the inner curved ends of the rods H, said rod H², however, forming a pivot upon which the cradle H made up of

- the bars H' may swing outward a limited distance, the straight shank portions of the bars H' in such swinging movement approaching a vertical position. It will be noted that the 5 cross-rod i' which connects the outer ends of the bars H' is adapted to normally rest upon the oppositely disposed beams A when in the position shown in Fig. 1 of the drawings, and in which position a slight space intervenes 10 between the inner curved ends of the bars H' and the bars H through which the sheets of metal pass to the discharge rollers described.
- In order to hold the two discharge rollers together, I have provided the hanger plates 15 D , a detail view of one being shown in Fig. 4 of the drawings. Said plates D are arranged in pairs upon the opposite faces of each beam A and each is provided with an inclined notch D' in which the ends of a pin G are adapted 20 to be seated, said pin being carried by the upright portion of the lever E , the lower angled end E' of which bears frictionally against the vertical edge of the box p . A handle e projects at right angles from the upright portion 25 of the lever E and affords means whereby the angled end of the lever may be pushed against the boxing b to cause the rollers to contact, the pivotal pin G being fulcrumed in the inclined groove or notch D' . A spring E^2 30 may be fastened to each of the handles E and provide means whereby the two rollers may be held normally in contact with each other, the one roller P yielding slightly to receive a sheet of metal drawn therethrough.
- 35 Mounted in threaded apertures in the boxes b of the frame B are the adjusting screws F , each of which has a cross-piece f at its top forming a means to rotate the screw, the lower end of each screw being 40 adapted to bear against the flange or top of a vat or pot, not shown, containing the molten metal with which the sheets of iron are to be coated.
- An apron K , being diagonally disposed, is 45 fastened at its upper end to a cross bar L , which has a sliding movement upon the upper edges of the bars A , while its lower end is pivotally mounted upon a rod h' passing through the bars H' . Said apron is provided 50 with a series of bars h which are pivotally connected at their lower ends to the rod h' and their upper ends to the cross bar L . The apron K , positioned as shown and described, 55 serves to deflect any flux or particles of dross which might otherwise adhere to the surfaces of the sheets of metal being coated and cause defects therein.
- The operation of my apparatus is as follows. The frame A being pivotally mounted 60 upon a vat, the cradles and rollers with the gear wheel fastened to one of the latter are adapted to be immersed in the molten metal with which the sheets of iron are to be coated. The cradles are so shaped that the sheets of 65 iron are caused to pass first downwardly

through the molten metal, thence caused to curve upwardly to the discharge rollers between which they are gripped and frictionally fed upward, thus allowing the sheets of metal to shed flux or other foreign substances 70 from the under surfaces thereof, the two discharge rolls being held at all times against the opposite faces of the sheets as they are being fed upward. As the solid gear wheel O is constantly turning in the molten metal, 75 the spaces intermediate the teeth thereof will be clogged with the metal and as the teeth thereof intermesh with the teeth M upon the hollow gear wheel, any accumulation of the molten metal will be cleared from the teeth 80 of the wheel and thus allow the apparatus to move smoothly without interruption. By means of the set-screws, the frame carrying the rollers and the cradles may be raised or lowered to gage the depth at which it may be 85 desired to have the rolls rest underneath the surface of the molten metal. In the event of it being desired for any purpose to have access to the space intermediate the fixed and the swinging cradle, as for instance to remove 90 a sheet of metal without its passing between the discharge rollers, the sheets being fed in between the cradles, the cradle made up of the bars H' may be swung up over the rollers, the apron having a sliding movement to allow 95 the swinging frame to move freely to the position shown in dotted lines in Fig. 1 of the drawings.

By the arrangement of the lever fulcrumed in the notches of the hangers D , said 100 levers may be readily removed by swinging the upright portions thereof forward, after which the boxes may be readily removed by sliding the same to the right and lifting them out between the spaces intervening between 105 the free ends of the hangers D and the upright portions of the drop frame B .

From the foregoing, it will be noted that by the provision of an apparatus as shown and described, a simple and efficient mechanism is afforded whereby a swinging cradle is provided to allow ready access to be had to the guideway through which the sheets pass, and the frame as well as the rollers allowed the adjustable movements set forth. 110 As the contact edges of the cradles are without obstructions, the sheets of metal will travel freely without any likelihood of becoming buckled by contact with projections such as screws, bolt heads, etc., which has 115 heretofore been an objection with machines commonly in use.

What I claim is:—

1. An apparatus for galvanizing iron, etc., comprising beams which are adapted to be pivoted at corresponding ends, a drop frame secured to said beams, adjusting screws mounted in said drop frames, discharge rolls mounted upon the latter, a fixed cradle fastened to said beams and frame, and an adjust- 130

able cradle pivotally connected at its inner end to said frame, as set forth.

2. An apparatus for galvanizing iron, etc., comprising beams which are adapted to be pivoted at corresponding ends, a drop frame secured to said beams, adjusting screws mounted in said drop frames, discharge rolls mounted upon the latter, a fixed cradle fastened to said beams and frame, an adjustable cradle pivotally connected at its inner end to said frame, the free end of said pivotal cradle normally resting upon said beams, and an apron hinged at its lower end to the pivotal cradle and having a sliding movement upon the upper edges of said beams, as set forth.

3. An apparatus for galvanizing iron, etc., comprising beams which are adapted to be pivoted at corresponding ends, a drop frame secured to said beams, adjusting screws mounted in said drop frames, discharge rolls mounted upon the latter, a cradle made up of bars which are curved edgewise, said bars being fastened at their outer ends to said beams and their inner ends to said frame, a swinging cradle made up of bars which are curved upon their edges, the inner ends of said swinging cradle pivoted to said drop

frame, and a rod fastened to the outer end thereof and resting upon said beams, as set forth.

4. An apparatus for galvanizing iron, etc., comprising beams which are adapted to be pivoted at corresponding ends, a drop frame secured to said beams, adjusting screws mounted in said drop frames, discharge rolls mounted upon the latter, a cradle made up of bars which are curved edgewise, said bars being fastened at their outer ends to said beams and their inner ends to said frame, a swinging cradle made up of bars which are curved upon their edges, the inner ends of said swinging cradle pivoted to said drop frame, a rod fastened to the outer end thereof and resting upon said beams, an apron pivotally connected to said swinging cradle at its inner end, and a rod fastened to the outer end of said apron and resting upon said beams, as set forth.

In testimony whereof I hereunto affix my signature in the presence of two witnesses.

SAMUEL E. ANDRESS.
